UNITED STATES PATENT OFFICE

CLAUDE L. POST, OF CHICAGO, ILLINOIS

TYPE ROLL

Application filed August 29, 1928. Serial No. 302,831.

My invention relates to improvements in type rolls and particularly to apparatus for removably securing printing devices in the type roll.

5 My invention has among its objects, the production of apparatus of the kind described which is simple, reliable, compact and satisfactory for use wherever found applicable.

10 A particular object of the invention is to provide improved apparatus for removably securing type, which apparatus may include either plates, individual type, linotype or printing slugs, in a type roll.

15 A further object is to provide means cooperating with a type roll for engaging the sheets, etc., being printed upon and for holding the same stationary, thus preventing slurring of the printing and "feather edges".

20 Many other objects and advantages of the construction herein shown and described will be obvious to those skilled in the art from the disclosure herein given.

25 To this end my invention consists in the novel construction, arrangement and combination of parts herein shown and described, and more particularly pointed out in the claims.

30 In the drawings, wherein like reference characters indicate like or corresponding parts:

35 Fig. 1 shows a sectional view through a printing machine having apparatus embodying my invention;

Fig. 2 is a plan view of a type roll shown in Fig. 1 and having type removably secured therein by means embodying the invention;

40 Fig. 3 is a detailed elevational view of a member forming a part of the invention;

Fig. 4 is a fragmentary sectional view taken on line 4-4 of Fig. 2;

Fig. 5 is a sectional view taken on line 5-5 of Fig. 2;

45 Fig. 6 is a sectional view taken on the line 6-6 of Fig. 2;

Fig. 7 is a fragmentary sectional view taken on line 7-7 of Fig. 5;

50 Fig. 8 is a fragmentary sectional view taken on line 8-8 of Fig. 5;

Fig. 9 is a sectional view taken on line 9-9 of Fig. 2;

Fig. 10 is a plan view similar to Fig. 2 but showing a plate, rather than type, engaged in the type roll; and

55 Figs. 11 and 12 are sectional views taken respectively on lines 11-11 and 12-12 of Fig. 10.

My invention is especially adapted for use in printing machines of the type disclosed and claimed in my copending application, Serial Number 741,428, filed October 3, 1924 and in my Patent 1,623,975 dated April 12, 1927.

60 The improved printing machine preferably comprises a frame 1, a type roll 3 and a platen or impression roll 4. The impression roll 4 may be provided with a tympan 2 and a feeding arc 2a arranged to cooperate with the type roll. The envelopes or other 65 matter to be printed upon are delivered between the rolls 3 and 4 by suitable means described in the application referred to above, the rolls being driven by other suitable means, also described in said application. 70

75 The type roll 3 is designed to carry any desired number of type 5, this type being either individual type, linotype, or similar slugs, or plates. As shown, the roll 3 has a groove 7 therein, the depth of the groove being such that when the type or slugs rest on the bottom surface 7a thereof (Figs. 4 and 5) the faces of the type will be properly disposed to cooperate with the roll 4. Extending longitudinally of the groove 7 in the side walls thereof are a pair of grooves 40. To retain the type or linotype slugs 5 in proper relation in the groove 7, I provide wedge-shaped spacers 8. However, I do not limit myself to the arrangement shown as obviously the spacers could be made to conform to type of any size and shape. 85

90 I will now describe the improved apparatus whereby I removably secure the type 5 in the printing roll 3, the printing roll 3 being particularly adapted to cooperate with the improved apparatus but being an essential element of the invention only to the extent indicated in the appended claims.

95 As best shown in Figs. 1 and 5, the print 100

ing roll 3 is provided with wedge-shaped slots 15, one of the slots 15 being disposed on each side of the groove 7, and a pair of slots 15' disposed diametrically opposite the 5 groove 7, although the latter slots may be arranged at any desired points on the periphery of the roll. In each of the wedge-shaped slots 15 are preferably provided a plurality of wedge-shaped members 16, the members 10 16 being removably and slidably mounted in the slots 15. Each of the members 16 may be threaded on a rod 17 as best seen in Fig. 7, the opposite portions of the rods 17 being preferably threaded in opposite directions as 15 indicated at 18 and 19 so that when one of the rods is revolved it will move its members 16 toward or away from each other. One end of each rod 17 may be squared as at 20 so that it may be engaged by a wrench or other suitable tool when it is to be rotated. The members 16 may be provided with projections 21 formed with inclined faces 22, which faces are adapted to engage type-clamping members 25.

25 Referring particularly to Fig. 3, these clamping members 25 comprise a block 30 having lateral flanges 31. These flanges 31 are adapted to seat in the grooves 40 in the side walls of the groove 7. Attached to the 30 upper surface of the block 30 by means of screws 32, or other suitable means, is a curved plate 33, the projecting ends 34 of which engage the surface 22 of the projections 21 of the members 16. It will be understood that 35 the plate 33 is curved so as to conform more or less to the curvature of the printing roll. When the members 25 are disposed in the groove 7, the tops of the plates 33 are not "type high" i. e. they are below the level of 40 the type surface.

Disposed opposite each other along the walls of the groove 7 are a pair of slots 41 extending longitudinally of the groove 7, these slots extend from the upper rear edge 45 of the wall of the grooves 40 to the surface of the roll. (See Figs. 4 and 6.) The purpose of this is to permit the members 25 to be lifted out of the groove 7, the slots just referred to forming passageways for the flanges 31 on 50 the block 30.

In practice, the members 16 and the rods 17 are first positioned in the wedge-shaped slots 15; the clamping members 25 are then positioned on the roll being either slipped on from 55 the ends or passed through the cut away portions 41, the type 5 and spacers 8 are then positioned in the groove 7, and finally the rods 17 are manipulated to draw the members 16 tightly against the plates 33 of the 60 clamping members 25, which plates bear against the ends of the type lines and prevent accidental displacement of the type relative to the printing roll.

Disposed on the printing roll outside of the 65 members 25, as shown in Fig. 2, are a pair of

members 50 formed of suitable material such as steel, or the like, and arcuate in form, as best seen in Fig. 9, one end 51 of each of these members being bent inwardly to engage in one of the slots 15'. These members are 70 slightly bowed beyond the circumference of the printing roll and are "type high". The function of these members 50 is to engage an envelope or sheet which is to be printed upon and thus hold it stationary relative to the 75 printing roll during the printing operation insuring accuracy of the impression and preventing blurring of the type and the formation of "feather edges", feeding it out of the machine when the impression has been made. These members extend to approximately 80 270°, although the arc may be widely varied, so long as they are sufficiently long to grip the type roll. By engaging the envelope or sheet, holding it stationary before the type has come into contact therewith, the members 50 prevent vibration of the stock when the machine is running at high speeds and thus are enabled to prevent slurring of the 85 printing and tearing of the stock.

Obviously, the bent portions 51 of the members may be engaged in any one of the slots 15 or 15' but will preferably be engaged in one of the slots 15'.

Referring now to Figs. 10 to 12, inclusive, these figures show a type roll 3 of the description previously described in which is disposed a plate 90 which represents a cut, half-tone or similar device for printing. The heart-shaped device 91 shown in Fig. 10 represents any material or device which is to be printed 100 from the plate 90. As shown, the plate 90 is arcuate in shape, being so curved as to seat snugly on the surface of the printing roll, and may be retained by means of the members 16 which are similar in construction to the members 16 previously described and are locked in place by rods 17 similar to the rods described above. While the plate 90 is shown as disposed over the groove 7, this is not at all necessary, as it may be arranged anywhere on the surface of the printing roll adjacent to any one of the grooves 15 or 15'. Furthermore, while the drawings 110 show the plate retained by four of the members 16, it has been found in practice that a single pair of members 16 carried by one rod 17 may be caused to grip the plate with sufficient force to retain it on the roll for the purpose of printing satisfactorily therefrom.

Having thus described my invention, it is obvious that various immaterial modifications may be made in the same without departing from the spirit of my invention; hence I do not wish to be understood as limiting myself to the exact form, construction, arrangement and combination of parts herein shown and described, or uses mentioned.

What I claim as new and desire to secure 125 by Letters Patent is:

1. A type roll having a longitudinal groove therein and having a longitudinal slot at each side of said groove, a clamping member slidably in said groove and extending over said slots, and means slidable in said slots for locking said clamping member in adjusted position. 70
2. A type roll having a longitudinal groove therein and having a longitudinal slot at each side of said groove, a clamping member having means thereon for engaging the sides of said groove, said clamping member being slidably in said groove and extending over said slots, and means slidable in said slots for locking said clamping member in adjusted position. 75
3. A type roll having a longitudinal groove with a groove countersunk therein, said roll also having a longitudinal slot at each side of said groove, a clamping member slidable in said groove and having means engaging said countersunk groove, said means and countersunk groove cooperating to retain said clamping member in said groove, means on said clamping member extending over said slots, and means slidable in said slots for locking said clamping member in adjusted position. 80
4. A type roll having a longitudinal groove therein and having a longitudinal slot at each side of said groove, a clamping member comprising a block slidable in said groove and a plate attached thereto extending over said slots, and means slidable in said slots and engaging said plate for locking said clamping member in adjusted position. 85
5. A type roll having a longitudinal groove with a groove countersunk therein, said roll also having a longitudinal slot at each side of said groove, a clamping member comprising a block slidable in said groove and a plate attached thereto extending over said slots, said block having a flange engaging said countersunk groove, said flange and said countersunk groove cooperating to retain said clamping member in said groove, and means slidable in said slots and engaging said plate for locking said clamping member in adjusted position. 90
6. A type roll having a longitudinal groove with a groove countersunk therein and said roll also having a longitudinal slot at each side of said groove, a clamping member slidably in said groove and having means slidably engaging said countersunk groove, said means and said countersunk groove cooperating to retain said clamping member in said groove, a portion of the oppositely disposed walls of said groove being cut away to permit the ready insertion of said clamping member into, and its withdrawal from, said groove, means on said clamping member extending over said slots, and means slidable in said slots for locking said clamping member in adjusted position. 95
7. A type roll having a longitudinal groove with a groove countersunk therein, said roll also having a longitudinal slot at each side of said groove, a clamping member comprising a block having means slidably engaging said countersunk groove and a plate attached thereto extending over said slots, and means slidable in said slots and engaging said plate for locking said clamping member in adjusted position. 100
8. A type roll having means for receiving printing means comprising a longitudinal groove, said roll having a longitudinal slot, a clamping member slidable in said groove engageable with said printing element, means in said slot for locking said clamping member in adjusted position, and means for moving said locking means in opposite directions to engage and release said clamping member. 105
9. A type roll having means for receiving printing means comprising a longitudinal groove, said roll having a longitudinal slot, a clamping member slidable in said groove engageable with said printing element, means in said slot for locking said clamping member in adjusted position, and means for moving said locking means in opposite directions to engage and release said clamping member, said last mentioned means including an element having opposed screw threads provided thereon. 110
10. A type roll having means for receiving printing means comprising a longitudinal groove, said roll having a longitudinal slot, a clamping member slidable in said groove engageable with said printing element, means in said slot for locking said clamping member in adjusted position, said roll having parallel grooves provided therein for engaging an arcuate member adapted to be removably associated with said roll. 115
11. A type roll having means for receiving printing means, said first mentioned means comprising a longitudinal circumferentially arranged groove and means for receiving means for engaging said printing means, said last mentioned means comprising longitudinally extending circumferential slots, arranged upon opposite sides of said groove, said groove having radial side walls. 120
12. A type roll having means for receiving a printing element, said first mentioned means comprising a longitudinal groove having a transverse slot whereby said printing element may be introduced to said groove, a longitudinal slot on opposite sides of said groove for the reception of locking means for locking an element in the said groove, said element having a member arranged transversely of said groove, said member providing means for engagement by said locking means. 125

13. A type roll having means provided therein for receiving printing means, said means of said roll comprising a longitudinal groove, said roll having a longitudinal slot arranged upon opposite sides of said groove, a locking member provided in said slots, and means extending from one slot to the other engageable by said locking member and providing means for engaging the printing means.

14. A type roll having means provided therein for receiving printing means, said means of said roll comprising a longitudinal groove, said roll having a longitudinal slot arranged upon opposite sides of said groove, a locking member provided in said slots, and means in said groove for engaging the printing element, said last mentioned means and roll being provided with means which cooperate with each other to hold said last mentioned means in said groove, said roll having a slot communicating with an arranged transverse to said groove providing means permitting association and removal of said last mentioned means with said roll, and said last mentioned means having means engageable with said locking member provided in said slots.

15. A type roll having means for receiving printing means, said first mentioned means comprising a longitudinal groove provided in said roll, a longitudinal slot provided in said roll, a clamping member slideable in said groove, and means in said slot for locking said clamping member in adjusted position.

In testimony whereof, I have hereunto signed my name.

CLAUDE L. POST.
